US00D767820S

(12) **United States Design Patent** (10) Patent No.: **US D767,820 S**
Jordan et al. (45) Date of Patent: ** Sep. 27, 2016

(54) **MOUTHPIECE FOR ELECTRONIC VAPING DEVICE**

D267,121 S 11/1982 Min
4,429,703 A 2/1984 Haber
4,945,929 A 8/1990 Egilmex
5,042,510 A 8/1991 Curtiss et al.
5,095,921 A 3/1992 Losee et al.
5,179,966 A 1/1993 Losee et al.
5,269,327 A 12/1993 Counts et al.

(71) Applicant: **Altria Client Services LLC**, Richmond, VA (US)

(72) Inventors: **Geoffrey B. Jordan**, Midlothian, VA (US); **Charles Dendy**, Richmond, VA (US); **Bipin Patil**, Richmond, VA (US)

(73) Assignee: **ALTRIA CLIENT SERVICES LLC**, Richmond, VA (US)

CN 202890464 U 4/2013
WO WO-2013089358 A1 6/2013

(**) Term: **15 Years**

(21) Appl. No.: **29/527,151**

(22) Filed: **May 15, 2015**

(51) LOC (10) Cl. **27-02**

(52) U.S. Cl.

USPC **D27/170**

(57) **CLAIM**

The ornamental design for a mouthpiece for electronic vaping device, as shown and described.

DESCRIPTION

FIG. 1 is a first perspective view of the mouthpiece for electronic vaping device;

FIG. 2 is a second perspective view of the mouthpiece for electronic vaping device;

FIG. 3 is a front view of the mouthpiece for electronic vaping device;

FIG. 4 is a side view of the mouthpiece for electronic vaping device; and,

FIG. 5 is a bottom view of the mouthpiece for electronic vaping device.

In the drawings, the broken lines depict environmental subject matter only and form no part of the claimed design.

1 Claim, 3 Drawing Sheets
